Attorney, Agent, or Firm—Norman B. Rainer

[57] **CLAIM**

The ornamental design for a rocking chair, substantially
as shown and described.

DESCRIPTION

FIG. 1 is a perspective view of a rocking chair showing
my new design.

FIG. 2 is a right side view thereof, the unshown left side
being of identical appearance.

FIG. 3 is a front view thereof.

The undisclosed rear portions of the rocking chair are
conventional in appearance.

FIG. 1

FIG. 2

FIG. 3
